Primary Examiner — T Chase Nelson

(74) Attorney, Agent, or Firm — Banner & Witcoff, Ltd.

(57) CLAIM

The ornamental design for a shoe, as shown and described.

DESCRIPTION

FIG. 1 is a front bottom perspective view of a shoe showing my new design;

FIG. 2 is a bottom view thereof;

FIG. 3 is a rear bottom perspective view thereof;

FIG. 4 is a side view thereof; and,

FIG. 5 is an opposite side view thereof.

The curved and oblique shade lines represent a translucent or transparent appearance. The broken lines depicting the remainder of the shoe show features that form no part of the claimed design.

1 Claim, 5 Drawing Sheets
